The ornamental design for a package for compressible material, as shown and described.

DESCRIPTION

FIG. 1 is a top plan view of a package for compressible material showing my new design;

FIG. 2 is a left side elevational view thereof;

FIG. 3 is a right side elevational view thereof;

FIG. 4 is a bottom plan view thereof;

FIG. 5 is a front end elevational view thereof;

FIG. 6 is a rear end elevational view thereof;

FIG. 7 is a top plan view of a second modified embodiment, the side opposite being a mirror image of the side shown;

FIG. 8 is a top plan view of a third modified embodiment, the side opposite being a mirror image of the side shown; and,

FIG. 9 is a top plan view of a fourth modified embodiment, the side opposite being a mirror image of the side shown.

FIG. 1

FIG. 2

FIG. 3

FIG. 4

FIG. 5

FIG. 6

FIG. 7

FIG. 8

FIG. 9
